UNITED STATES PATENT OFFICE.

WILLIAM B. BURGET, OF KANSAS CITY, MISSOURI.

VENDING-MACHINE.

1,268,212.

Specification of Letters Patent.

Patented June 4, 1918.

Application filed March 10, 1917. Serial No. 153,957.

To all whom it may concern:

Be it known that I, WILLIAM B. BURGET, a citizen of the United States of America, residing at Kansas City, in the county of

5 Jackson and State of Missouri, have invented certain new and useful Improvements in Vending-Machines, of which the following is a specification, reference being had therein to the accompanying drawing.

10 This invention relates to a vending machine and has for its principal object the production of a simple and efficient device wherein means is provided for dispensing the articles carried by the device.

15 Another object of this invention is the production of a vending machine wherein simple and efficient coin-controlled means is employed for dispensing singly the articles carried within the machine.

20 Another object of this invention is the production of a vending machine wherein slides are employed in connection with movable triggers in such a manner as to allow the coin carried by the slide to engage and 25 operate the trigger for moving the tripping arm, thereby dispensing an article carried by the machine.

Another object of this invention is the 30 production of a vending machine wherein the articles carried therein are held so as to be guarded against unauthorized removal although upon the insertion of a coin in the slide the machine will be positively operated for dispensing a single article.

35 With these and other objects in view this invention consists in general of certain novel combinations, constructions and arrangements of parts as will be hereinafter fully described and claimed.

40 In the accompanying drawings:

Figure 1 is a front elevation of the complete vending machine as constructed in accordance with this invention.

45 Fig. 2 is top plan view of the vending machine.

Fig. 3 is a central vertical section through the vending machine.

Fig. 4 is a horizontal section taken on the line 4-4, Fig. 3, looking in the directions 50 of the arrows, a portion of the device being removed.

Fig. 5 is a plan view of a portion of a certain supporting plate used in connection with the slides.

55 Fig. 6 is an enlarged vertical section through the lower portions of the vending

machine taken on the line 6-6, Fig. 1, and looking in the direction of the arrows.

Fig. 7 is a horizontal section through the lower portions of the machine, illustrating 60 a portion of the coin drawer carried thereby.

Fig. 8 is a section taken on the line 8-8, Fig. 4.

Fig. 9 is an enlarged detail perspective 65 view of one of the slides.

Fig. 10 is a detail perspective view of one of the tripping arms.

Fig. 11 is a vertical section taken on the line 11-11, Fig. 6, looking in the direction 70 of the arrows.

Fig. 12 is a section taken on the line 12-12, Fig. 4.

Fig. 13 is a detail perspective view of one of the triggers.

Referring to the accompanying drawings by numerals it will be seen that the vending machine comprises a casing formed of a base 1 having the usual supporting pads 2 thereon, and from this base 1 extend the parallel 80 sides 3 and a back 4. It will be noted, however, that the sides 3 are broadened adjacent their lower ends as indicated at 5 to provide sufficient space for the operating mechanism of the vending machine which 85 will be hereinafter described. It is obvious that the sides 3 and the back 4 may be countersunk as shown at 6 in the usual manner for reinforcing and steadyng the lower portions of the sides and back. The sides 3 90 are provided with vertically-extending alined grooves 7 so as to receive the sliding front 8 as shown clearly in Figs. 1, 3 and 6. This front 8 is provided with a thin solid panel 9 adjacent its upper portion. Adjacent the lower end of this sliding front, there is provided a glass panel 10 of a bevel construction as shown in Fig. 3. This sliding front 8 is removably held upon the sides 3 by means of the removable top 11 which is 95 positioned upon the upper ends of the sides 3, the back 4 and the sliding front 8, as shown in Fig. 3. This top 11 is provided with grooves 6' for the reception of the upper ends of the sides, back and front for reinforcing these elements and preventing the top from being pried from engagement therewith.

In order to removably hold this top 11 upon the upper end of a vending machine, 110 there is provided a flattened bar 12 having an offset lower end 13. This bar 12 passes

through the base 1 of the vending machine so as to permit the offset end 13 thereof to engage the outer surface of this base, thereby limiting the upward movement of the bar. The bar, however, moves entirely 5 through the vending machine and also through the removable top 11 thereby permitting a bearing plate 14 to be positioned over its projecting end, while a padlock 15 engages this projecting end for releasably holding the bar 12 in engagement with the vending machine, thereby holding the vending machine in a closed position for preventing the same from being opened by an unauthorized party.

10 The back 4 is provided with a plurality of vertically-extending ribs 16 fixedly mounted thereon in any suitable manner and carried in spaced relation with respect to each other, as shown clearly in Fig. 4. The outer edges of these ribs 16 are provided with vertically-extending flanges 17 held thereon by means of rivets or tacks 18. These flanges 17 project for considerable 15 distances beyond the side surfaces of the ribs 16 and therefore constitute retaining chutes in which the articles to be vended by the machine are carried. The upper ends of these chutes are opened, as shown in Fig. 3, but at the lower ends of these chutes there is carried a slanting supporting shelf 19. This supporting shelf 19 extends across the entire width of the vending machine having its end portions bearing upon the 20 under surfaces of the sides 3 as shown in Fig. 4. Auxiliary dividing ribs 20 project from the lower ends of the ribs 16, as shown clearly in Fig. 6 and, therefore, prevent the articles passing from the lower ends of the 25 various chutes from becoming mixed. It will be noted, however, that a flange 21 is fixedly mounted upon the forward edge of this shelf 19, this flange 21 having its lower portions reinforced by the molding 22. This 30 flange 21 projects above the upper surface of the shelf 19 and, as a consequence, prevents the articles carried by the chutes from rolling off the shelf 19 owing to its slanting construction. It is, of course, obvious that 35 the chutes 19 may be of such construction as will enable various kinds of goods to be carried thereby, although in the present application bottles are shown in full lines in Fig. 6 and in dotted lines in Fig. 3 to illustrate the operation of the machine. It will 40 be seen that the bottles are inserted at the upper ends of the chutes and then the bottles pass down so as to rest upon the shelf 19, rolling or abutting against the flange 45 21. In order to remove the bottles from the shelf it is necessary to employ an operating mechanism which will be hereinafter 50 described.

55 The parallel base bars 23 are carried by 60 the lower portions of the sides 3 whereby the

ends of these base bars 23 will engage the broadened lower portions 5 of the sides 3, as shown in Fig. 3. These bars being carried in spaced relation support the base supporting plate 24 of the operating mechanism. This base plate 24 is provided with a number of openings 25 through which the coin carried by a particular slide is adapted to fall when the article desired is being dispensed. The bearing strips 26 are fixedly retained in spaced relation upon the base plate 24 by means of the bolts 27 while the forward portions of these bearing strips 26 are reinforced by the auxiliary bearing strips 28. It will be further noted by referring particularly to Figs. 4, 5 and 12 that guiding tongues 29 are struck in parallel relation from the base plate 24 so as to be bent upwardly and provide overhanging portions for constituting guides adjacent the outer side edge of the base plate 24. It is of course obvious and it will be seen by referring particularly to Fig. 12 that the base plate 25 may be retained upon the bars 23 by means of the screws 30 or any other suitable securing elements desired.

55 The slides are similarly constructed and by referring particularly to Fig. 9 the construction of the slides will be apparent. Each slide comprises a body 31 having 95 straight side edges 32 and having a grip 33 bent upwardly at its outer end. The arms 34 extending from the inner end of the body 31 are provided with inwardly-extending lugs 35 for purposes to be hereinafter set forth. Each body 31 is also provided with a coin opening 36 communicating with a slot 37 leading from the space between the arms 34. It should further be noted that one of the arms 34 is cut away on one side to provide an elongated notch 38. The slide is positioned upon the base plate 24 as shown clearly in Fig. 4 so as to fit between the bearing strips 26 and to be engaged by the bearing tongues 29. These tongues 29 overhang the outer surface of the slides 31 and, as a consequence, the action of the strips 26 and the tongues 29 will cause the slides to be firmly held although the same will freely slide when the operator grips the vertical grip 33 of the slide and moves the same in either direction. The movement of the slide in either direction is limited, however, by means of the pin 39 carried by the base plate and fitting within the notch 38 of one of the arms 34 of the slide. By forming the elongated notch 38 it is obvious that at each end of the notch, abutment shoulders 38' will be formed whereby the engagement of either abutment shoulder 38' and the pin 39 will 115 limit the movement of the slide in either direction.

120 The trigger comprises a body 40 having a shank 41 formed thereon and extending for a considerable distance whereby an elong- 130

gated slot 42 may be formed in the body 40 and shank 41 as shown in Fig. 13. The body 40 is also provided with outwardly-extending ears 43 for purposes to be hereinafter set forth. The trigger 40 is positioned upon the base plate 24 and fits between the arms 34 of the slide 31, as shown clearly in Fig. 4. In order to retain the trigger in slidable engagement with the base plate 24, a headed pin 44 passes through the slot 42 which projects through the base plate 34. This pin 44 is held in yieldable engagement with the slide 40 by means of the coil spring 45 positioned thereon and bearing at one end 15 against the lower portions of the base plate 24 and at its opposite end against the washer 46 held upon the pin 44 by means of a cotter pin 47. The shank 41 of the trigger 40 will at all times project through the slot 37 20 formed in the slide 31 as shown in Fig. 4. When it is desired to operate the trigger, the slide is pulled outwardly, as shown at the right-hand portion of Fig. 4, and at this time a coin may be inserted in the coin opening 36 of the slide 31. Then by pushing the slide inwardly the coin will bear upon the end of the shank 41, thus causing the trigger to be pushed inwardly simultaneously 25 with the inward movement of the slide for operating the tripping arm to be hereinafter described. If the slide is pushed inwardly without a coin being carried within the opening 36 thereof, it is obvious the trigger will not move since no means is employed 30 for pushing the trigger inwardly other than the coin above referred to. Of course after the trigger has been pushed inwardly by the coin carried within the opening 36 of the slide 31 and the coin falls from the opening 36 through the opening 25 formed in the base plate 24 and the outward movement of the slide is again started, the lugs 35 of the arms 34 will engage the ears 43 of the body 40 of the trigger, thus pulling the trigger 45 from one position as indicated in Fig. 4 to the position shown at the right-hand portion of Fig. 4. The cover plate 48 is positioned above the base plate 24 so as to cover the trigger, portions of the slides and the auxiliary strips as shown in Figs. 3, 4 and 6, thereby holding the elements in engagement with each other and thus relieving tension 50 from the retaining elements above described. The inner base bar 23 is provided with a plurality of notches 49 so as to permit the plates 50 to be passed therethrough and rest upon the lower surfaces of the base plate 24. The bolts 51 carried by the base plate 24 project through the plates 50 for fixedly retaining the plates 50 upon the base plate 24. These plates 50 have integral rests 52 projecting therefrom and these rests 52 are bent upwardly to provide upwardly-extending ends 53 adjacent their inner portions. The 55 upwardly-projecting portions 53 project

above the cover plate 48 as shown clearly in Figs. 3 and 6, while journals 54 are bent upwardly from the side edges of the rests 52 as shown clearly in Figs. 6 and 11.

The tripping arms are similarly constructed and by referring to Fig. 10 it will be seen that each tripping arm comprises an elongated body 55 having a bearing 56 formed at its lower end through which extends the opening 57. At the opposite end of the body 55 there is provided a tripping finger 58 having the bevel surface 59. The bearing 56 is positioned between the journals 54 so as to permit the pivot pin 60 to be passed through the opening 57 and be carried by the journals 54 for pivotally mounting the tripping arm upon the rest. Since the vertical portion 53 of the tripping arm projects for a considerable distance above the lower portions of the rest, it is obvious that the tripping arm will be held in an inclined position as shown in Fig. 6.

It will be noted that the shelf 19 is provided with a plurality of notches 61 through which the tripping fingers 58 of the tripping arms 55 project at all times, so as to be in position to readily engage the articles carried by the shelf when the tripping arms are actuated.

95

For the purpose of receiving the articles dispensed from the vending machine, there is carried a tray 62 mounted at its inner portion upon the strip 63 carried upon the outer surface of the flange 21. The outer portion of the tray 62 is carried upon the bar 64 resting upon the cover plate 48 and bearing at its ends against the enlarged lower portions 5 of the sides 3. A strip of molding 65 having a straight inner surface 66 is carried so as to rest upon the tray 62 for preventing the articles dispensed onto the tray from rolling therefrom. It will be noted by referring particularly to Fig. 6 that the lower end of the sliding front 8 is carried at a distance from the upper surface of the tray 62, thereby providing sufficient space for an article dispensed from the shelf 19 to pass over the flange 21 and under the sliding front 8 to be carried by the tray 62 adjacent the straight inner surface 66 of the molding 65. From this position it is obvious that the operator of the vending machine can easily procure the article so vended.

100

105

110

115

120

The coin drawer is inserted below the supporting beams 23 and comprises the side bar 67 and the front bar 68 and the rear bar 69. The bottom 70 is carried by these bars, although it will be seen by referring to Figs. 6 and 7 that the side bars 67 project from a considerable distance beyond the rear bar 69. The coil spring 71 is carried by the bracket 72 upon the rear bar 69 as shown in Fig. 7, and this coil spring 71 bears against

the back 4 of the casing of the vending machine for normally urging the coin drawer outwardly. This drawer, however, is normally held in a closed and locked position by the action of the bar 12 which projects through the rear bar 69 and since this bar 12 is held in a locked position upon the vending machine, the drawer will be positively held in a locked and closed position. When, however, it is desired to remove the drawer from the lower portions of the vending machine, the bar 12 may be withdrawn and at this time the tension of the spring 71 will move the drawer outwardly, thereby permitting the operator of the machine to empty the drawer when desired.

When this machine is in operation, it is first necessary to fill the same. In order to accomplish this purpose the padlock 15 is removed and the bar 12 withdrawn from the casing of the vending machine by pulling upon the offset end 13 of the bar 12. After the bar 12 has been removed, the removable top 11 is then taken from the upper end of the machine so as to permit the sliding front 8 to be removed. At this time the removal of the bar 12 will also cause the coin drawer to move outwardly from the lower portion of the vending machine. The chutes may then be filled with the articles to be vended so as to permit the articles to pass downwardly over the upper surfaces of the shelf 19 to abut against the flange 21 as hereinbefore described. After the chutes have been filled and the coin drawer emptied, the coin drawer is then moved inwardly so as to permit the bar 12 to be passed from the base 1 of the vending machine and then through the drawer so as to hold the drawer in a closed position. The bar 12 then passes upwardly through the shelf 19 at which time the sliding front is positioned within the grooves 7 of the sides 3. It should be noted by referring particularly to Fig. 3 of the drawing that the sliding front is also provided with a reinforcing strip 8' which projects inwardly from the front 8 and bears against the forward portions of the chutes. After the sliding front has been positioned upon the sides 3, the removable cover is then placed upon the upper ends of the sides, back and front and then the upper end of the bar 12 is passed beyond the strip 8' and projects through the top 11 so as to receive the padlock 15 for holding the vending machine in a closed position.

When a party desires to purchase one of the articles carried within the chutes he must first pull one of the slides 31 outwardly so as to expose the coin opening 36 thereof. The coin is positioned within the opening 36 and then the slide is moved inwardly so as to cause the coin carried within the

opening 36 of the particular slide to abut against the end of the shank 41 of the trigger 40. Continued inward movement of the slide will cause the trigger to be moved inwardly until the inner end of the body 40 abuts against the journal 56 of the tripping arm 55, thereby swinging the opposite end of the tripping arm upwardly since the pressure upon the tripping arm will take place below the plane of the pivot of the tripping arm. Since the finger 58 projects into a notch of the shelf 19 as shown in Fig. 6 it will move upwardly into engagement with the foremost article, lifting the same upwardly to pass over the upper portion 80 of the flange 26 as indicated in dotted lines in Fig. 6. As soon as the article which is in this case a bottle passes above the flange 21, it will then pass under the lower end of the front 8 and will roll down the tray 62 to abut against the molding 65. When the slide has been moved far enough inwardly to cause the trigger to swing the tripping arm upwardly, the coin opening 36 of the slide will register with the opening 90 25 of the base plate 24 whereby the coin will fall from the opening 36 through the opening 25 into the coin drawer carried therebelow, as shown in Fig. 6. As soon as the coin falls into the coin drawer, the weight of the tripping arm 55 will cause the tripping arm to return to its normal position to rest upon the vertical portion of the rest 52 thereby causing the trigger 40 to be pushed slightly toward the forward portions of the vending machine. It is obvious that continued inward urging of the slide 31 will not affect the trigger since the slide is not provided with any elements which can possibly urge the trigger inwardly. If another article is desired, the slide is pulled outwardly and at this time the lugs 35 thereof will pull upon the ears 43 of the trigger, thus moving the trigger outwardly from the tripping arm until the slide is limited in its outward movement by means of the pin 39. It is, of course, obvious that as many bottles or other articles carried within the vending machine may be obtained as desired by repeated action as above disclosed. As soon as the machine has been emptied, it may be refilled as has also been disclosed and it is, of course, understood that the operation of all the slides is similar.

It is not desired to limit the disclosure or construction of this invention to the specific structure herein shown for many minor details may be made in the device such, for instance, as the increasing or diminishing in size of the tongues 29. Therefore, it is intended to include all such forms of the invention as properly come within the scope thereof as claimed.

From the foregoing description it will be seen that a very efficient vending machine

has been provided wherein the articles carried thereby are dispensed by the operation of a coin carried by the slide and operating upon the trigger for swinging the tripping arm.

5 What is claimed is:—

In a device of the class described, the combination of a casing, dispensing means carried thereby, a slide reciprocally mounted upon said casing, said slide comprising a body having parallel arms projecting therefrom, lugs formed upon the inner ends of said arms, said body having a coin opening formed therein and a slot projecting from the coin opening, one of said arms having an elongated notch formed upon its outer side, thereby forming abutment shoulders, a pin carried by said casing and projecting into said notch, whereby the movement of said slide will be limited, a trigger comprising a body having a slotted shank extending therefrom, outwardly extending ears formed upon said body, said shank extend-

ing into said slot of said slide, a pin carried by said casing and projecting through the slot of said shank, whereby said trigger will be held against side movement, said casing having a coin discharge opening, said slide being adapted to receive a coin within said coin opening, whereby as said slide is pushed inwardly the coin will engage said shank for forcing said trigger into engagement with said dispensing means, thereby causing said dispensing means to be operated, the coin opening of said slide then registering with the coin discharge opening in said casing, whereby the coin will move from engagement with said slide, said slide then being adapted to be pulled to its normal position, whereby said lugs will engage said ears for moving said trigger from engagement with said dispensing means.

10 15 20 25 30 35 40
In testimony whereof I hereunto affix my signature.

WILLIAM B. BURGET.
